[57] CLAIM

The ornamental design for a stereo radio, as shown and described.

DESCRIPTION

FIG. 1 is a top, front and right side perspective view of a stereo radio showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof, the left side being a mirror image; and

FIG. 7 is an inverted top, front and right side perspective view of a second embodiment of the stereo radio illustrated in FIG. 1.

FIG 1**FIG 3****FIG 2**

FIG 4**FIG 5****FIG 6****FIG 7**
